UNITED STATES PATENT OFFICE.

LEWIS E. KINGMAN, OF NORTHAMPTON, MASSACHUSETTS, ASSIGNOR TO FANNIE B. LOOK, OF NORTHAMPTON, AND ELDON MACLEOD, OF WESTWOOD, MASSACHUSETTS, AND GEORGE H. BURR, OF NEW YORK, N. Y., TRUSTEES, DOING BUSINESS AS FLORENCE MANUFACTURING COMPANY.

DESIGN FOR A DISPLAY-CASE.

46,999.

Specification for Design.

Patented Feb. 23, 1915.

Application filed October 21, 1914. Serial No. 867,909. Term of patent 3½ years.

To all whom it may concern:

Be it known that I, LEWIS E. KINGMAN, a citizen of the United States, residing at Northampton, in the county of Hampshire and State of Massachusetts, have invented a new, original, and ornamental Design for a Display-Case, of which the following is a specification, reference being had to the accompanying drawings, forming a part thereof.

The drawing is a view in perspective of a display case showing my new design.

I claim:

The ornamental design for a display case as shown.

LEWIS E. KINGMAN.
